UNITED STATES PATENT OFFICE

93,636

DESIGN FOR A COMBINED DISPLAY CASE AND TRAY

Lester M. Sawin, Chicago, Ill.; Emilyn J. Sawin, administratrix of said Lester M. Sawin, deceased, assignor to The Susu Nut Company,
Chicago, Ill., a corporation of Illinois

Application January 6, 1934, Serial No. 50,338

Term of patent 7 years

To all whom it may concern:

Be it known that I, LESTER M. SAWIN, a citizen of the United States, residing at Chicago, in the county of Cook, and State of Illinois, have invented a new, original, and ornamental Design for a Combined Display Case and Tray, of which the following is a specification, reference being had to the accompanying drawing forming part hereof, in which

Figure 1 is a front perspective view of the combined display case and tray, showing my new design.

Fig. 2 is a rear perspective view thereof.

I claim:

The ornamental design for a combined display case and tray as shown.

LESTER M. SAWIN.
